UNITED STATES PATENT OFFICE.

JOHANN CONRAD KUNST, OF BRAKE, GERMANY.

MEANS FOR PROPELLING SHIPS.

No. 802,648.

Specification of Letters Patent.

Patented Oct. 24, 1905.

Application filed December 20, 1904. Serial No. 237,692.

To all whom it may concern:

Be it known that I, JOHANN CONRAD KUNST, merchant, a subject of the Grand Duke of Oldenburg, residing at Brake, in the Grand Duchy of Oldenburg, in the German Empire, have invented certain new and useful Improvements in Means for Propelling Ships, of which the following is a full, clear, and exact description.

The present invention relates to improvements in means for propelling ships; and it substantially consists in arranging within a paddle-wheel a motor adapted to drive the said wheel. This motor can be a steam-turbine, an electromotor, or any other motor suitable for the purpose.

In the annexed drawings one form of the invention is illustrated by way of example.

Figure 1 is a longitudinal section of a paddle-wheel provided with a turbine-engine, the axis of revolution of the said wheel being at right angles to the longitudinal axis of the ship. Fig. 2 is a section of the paddle-wheel and casing with the engine removed.

In the case illustrated the wheel is on the starboard side of a steamer and an exactly similar wheel and engine are arranged on the port side of the vessel, and the two engines can be run in the same direction, forward or backward, or, if necessary, one of them can be reversed, as in the case of a twin-screw steamer.

The paddle-wheel comprises a cylindrical water-tight drum 11, provided at its outer circumference with fixed paddles 12, which are comparatively long, but not of great width. This drum is fixed to the outer casing 13 of a turbine—for instance, a Parson turbine—so that when this casing is revolved by the action of the steam the drum is also revolved. The water carried upward by the paddles is discharged through the openings 32 in the fixed sheet-iron box or casing 33 and then flows downward therein. For the purpose of preventing damage to the paddles by coming into contact with the ground keels 34 are provided, which extend downward below the level of the outer edge of the lowermost paddle-blade.

The turbine-casing is provided at both ends with hollow journals 14 and 15, one of which, 14, serves for the exhaust of steam from the turbine. The exhaust steam passes through the vertical tube 15' into the condenser. The hollow journals 14 and 15 are supported by bearings 18, which can, for instance, be provided in the usual manner with brasses of white metal or pockwood. Said bearings can

be screwed firmly to the lateral walls of the wheel-box 17.

For the purpose of protecting the turbine against cooling a thick layer of felt 19 can be provided, and an inner drum 20, fitting tightly into a stuffing-box 21, is provided to prevent the entrance to the chambers 23 of the seawater which may penetrate through the joint between the circumference of the flanges 22 and the outer drum 11 of the wheel. A layer of felt 24, impregnated with oil and inserted between the drums 11 and 20, serves for further insulating the heat. It may therefore be assumed that the loss of energy through condensation is not greater than usual, notwithstanding the arrangement of the turbine inside the paddle-wheel.

The live steam is supplied to the turbine through the tubular shaft 25, which is prevented from rotating by two horizontal bolts 26. With this shaft communicates the inner casing 27 of the turbine, to which is fixed one of the sets of the turbine-blades. This inner casing is not rotatable, contrary to the usual practice in turbines of this kind, and is fixed to the tubular shaft 25. The latter has therefore to bear the whole torque of the engine and must be of sufficient strength to resist the rotational strains and the strains resulting from the internal steam-pressure. To the flange 28 can be directly connected the main steam-valve or a throttle-valve adapted to be operated by means of a hand-lever. The tubular shaft 25 is steam-tight with regard to the chamber 30 of the turbine by means of a stuffing-box 29, so that no steam can pass from said chamber 30 into the engine-room. The tubular shaft 25 is preferably supported by the bolts 26, already referred to, so that the dead-weight of the inner body of the turbine does not bear on the stuffing-box. The right-hand end of the inner casing 27, as seen in Fig. 1, is supported, by means of a hollow journal 30', in a bearing 31, which is integral with the box or casing 32' and with the gudgeon 14. To the bearing 31 is also fixed the small bearing 33', which prevents the displacement of the inner turbine-casing with regard to the outer turbine-casing. The inner bearings 30' and 31 can be supplied with oil through the axial lubricating-tube 34'. The other bearings and the stuffing-box 29 can be approached from the engine-room, so that their lubrication does also not present any difficulties.

As the outer drum 11 of the paddle-wheel

is only fixed to the turbine at one end and revolves loosely on the flanges 22 at the other end and since the stuffing-box 21 allows of displacement of the turbine with regard to 5 the drum 20, injurious strains resulting from the heating of the turbine cannot be produced in the longitudinal direction of the wheel.

In the form of construction illustrated the turbine-casing is coupled directly with the 10 wheel-drum; but there is of course no obstacle to the use of an indirect coupling, so that the turbine, notwithstanding its arrangement inside the wheel, can rotate far more rapidly than the latter. It may be stated, 15 moreover, that the paddles of the wheel can also be of angular or zigzag shape in order to reduce their impact with the water.

What I claim as my invention, and desire to 20 secure by Letters Patent, is—

1. The combination with the hull, of a water-tight casing mounted therein and opening into the water, journals at the opposite ends 25 of the casing, a rotary drum within the casing and arranged to revolve in the said journals, the drum being provided on its exterior surface with paddles, a turbine within the drum and secured directly thereto, and connections with a source of steam-supply for causing the turbine to rotate, substantially as 30 set forth.

2. The combination with the hull and a water-tight casing mounted therein opening into the water, of hollow journals at the opposite ends of the casing, a turbine rotatably mounted 35 in said journals, a water-tight drum provided with paddles, and connections through said hollow journals for admitting the motive fluid to the turbine and exhausting it therefrom, substantially as set forth.

3. The combination with the hull and a casing mounted therein opening into the water, of hollow journals at the opposite ends of the casing, a turbine rotatably mounted in said journals, a water-tight drum provided with 45 paddles, connections through said journals for admitting the motive fluid to the engine and exhausting it therefrom, and heat-insulating means arranged between the turbine and the water-tight drum, substantially as set forth.

4. The combination with the hull and a casing supported therein and opening into the water, of hollow journals at the opposite ends

of the casing, a paddle-wheel comprising a water-tight drum rotatably supported in said journals, and a turbine arranged within the drum, the inner casing of the turbine being stationary and secured within the hollow bearings and the outer casing thereof being secured to the drum and arranged to revolve about the inner casing, whereby motion is imparted to the said drum, substantially as set forth. 55

5. The combination with the hull provided with a casing opening into the water, of a water-tight drum arranged therein and provided 60 with paddles, a turbine-engine concentrically arranged within the drum, the end through which the motive fluid is delivered to the engine being secured to one head of the drum and the opposite head of the drum being provided with a thrust-bearing, and connections with a source of supply for admitting the motive fluid to the turbine-engine, substantially as set forth. 70

6. The combination with the hull and a casing opening into the water, journals at the opposite ends of the casing, a water-tight drum mounted in said journals, a turbine arranged within the said drum, the inner casing of the turbine being stationary and the outer casing being rotatable and secured to the drum to rotate the same, and a stuffing-box arranged between the outer casing of the turbine and the drum to prevent the entrance of water therebetween, substantially as set forth. 75

7. The combination with the hull of a vessel provided with a casing opening into the water, of a paddle-wheel mounted in the casing and comprising a tight drum to which the 90 paddles are secured, a turbine-engine for driving the paddle-wheel mounted within the drum thereof and consisting of a hollow rotating member carrying impact-blades, means for directing the motive fluid against the impact-blades, and means for conveying away the motive fluid after it has performed its work, 95 substantially as set forth.

In witness whereof I subscribe my signature in presence of two witnesses.

JOHANN CONRAD KUNST.
